Primary Examiner — John Windmuller*Assistant Examiner* — John R Yeh**CLAIM**

The ornamental design for a cleansing article, as shown and described.

DESCRIPTION

FIG. 1 is a front perspective view of a cleansing article; FIG. 2 is a front view of a cleansing article; FIG. 3 is a back view of a cleansing article; FIG. 4 is a left side view of a cleansing article; FIG. 5 is a right side view of a cleansing article; FIG. 6 is a top view of a cleansing article; FIG. 7 is a bottom view of cleansing article; and, FIG. 8 is an enlarged view of a portion of the cleansing article.

The broken lines in the drawings show portions of the cleansing article which form no part of the claimed design. The dash dot dot lines of FIG. 1 represent the portion of the article which is shown in FIG. 8 and form no part of the claimed design.

1 Claim, 6 Drawing Sheets(56)
